UNITED STATES PATENT OFFICE.

JOHN F. KINNEY, OF HUMBOLDT, KANSAS.

AEROPLANE.

1,296,528.

Specification of Letters Patent.

Patented Mar. 4, 1919.

Application filed February 16, 1917. Serial No. 149,064.

To all whom it may concern:

Be it known that I, JOHN F. KINNEY, a citizen of the United States, residing at Humboldt, in the county of Allen and State 5 of Kansas, have invented new and useful Improvements in Aeroplanes, of which the following is a specification.

This invention relates to improvements in aeroplanes or flying machines of the heavier-than-air class, the object of the invention being to provide a machine having novel means for maintaining automatic stability, thus securing safety in flight and allowing the pilot or aviator to have free use of his 10 hands, when desired, for performing operations other than the direct work of controlling the machine, such as taking observations or gathering other data, firing a gun, sending or receiving wireless messages, etc.

20 A further object of the invention is to provide an aeroplane which is light, strong and durable in construction, capable of attaining high speed, and which is therefore adapted for military use, commercial and 25 other purposes, wherein the employment of a fast traveling and good load carrying machine is required, and which may embody any suitable type of base to adapt it for land or marine use.

30 With these and other objects in view, the invention consists of the features of construction, combination and arrangement of parts hereinafter fully described, and claimed, reference being had to the accompanying drawings in which:-

Figure 1 is a top plan view of a flying machine embodying my invention.

Fig. 2 is a side elevation of the same.

Fig. 3 is a vertical longitudinal section, 40 taken on the line 3—3 of Fig. 1.

Fig. 4 is a sectional plan view on the line 4—4 of Fig. 2.

Fig. 5 is a diagrammatic perspective view of the lateral stabilizing gear.

45 Fig. 6 is a diagrammatic perspective view of the longitudinal steering and stabilizing gear.

Fig. 7 shows the propeller and clutch in detail.

50 Referring now more particularly to the drawings, 1 designates the main frame of the machine, which may consist, as ordinarily, of the upper and lower plane frames of a biplane structure, together with the connecting stanchions or struts, the machine structure shown in the present instance be-

ing of the biplane type and including the upper and lower supporting planes 2 and 3. The main frame, with its supporting surface, is mounted upon a suitable forward 60 under-carriage or launching and alighting structure shown in the present instance as consisting of a base frame work 4 carrying skids or pontoons 5 and suitably cushioned wheels 6. In addition to the fore-carriage, 65 constructed as above described, I provide the machine with a tail frame 7 of suitable construction carrying a supporting wheel 8 arranged at or adjacent to the front end of the tail frame, and a rear skid or pontoon 9, arranged at a point just in rear of the transverse center of said tail frame. In the present instance I have particularly illustrated the use of pontoons in place of skids or runners, to render the machine capable of alighting upon, traveling along and ascending from a body of water. The tail frame is reinforced from the main frame by suitable braces 10 and carries a rear horizontal rudder or elevator 11 and a vertical 70 rudder 12, which are pivoted to swing in respective planes at right angles each to each in the usual manner.

75 The supporting surfaces 2 and 3 may be of a suitable aggregate supporting area and 80 curved to present a desired angle of incidence, and preferably, as shown, the upper surface 2 is arranged partially in advance of the lower surface 3, so as to obtain an increased degree of longitudinal stability in 85 flight. The machine is driven by a tractor propeller 13 which is mounted upon a shaft 14 adapted to be thrown into and out of connection with the shaft 15 of a driving motor 16 by means of a suitable clutch device 17, controlled by a pedal or foot lever 18 by means of which the aviator may throw the propeller into and out of action at will without stopping the motor. The lever 18 is arranged in proximity to the 90 aviator's seat 19 which is disposed upon the main frame at a point below the trailing edge of the upper plane 2 and in rear of the leading edge of the lower plane 3, so that the weight of the aviator will be properly disposed with relation to the centers of gravity and pressure of the machine to assist in securing a maximum degree of normal poise or stability.

100 The rudders 11 and 12 are connected by 110 means of sets of control wires 20 and 21 with control levers 22 and 23, pivotally

mounted upon the main frame to swing in a fore-and-aft direction, whereby said rudders may be conveniently operated. The rudder 11 is also adapted to be actuated by 5 an automatic control device consisting of a weighted pendulum lever 22' mounted to swing upon the underside of the main frame in a fore-and-aft direction and having a crank 23^a connection with a rod 23^b which is 10 connected with the control lever 22. When the machine is in normal flight and properly balanced in the longitudinal direction, the lever 22 is maintained by gravity in its normal position with respect to the gliding 15 structure, but when the machine tilts unduly either forward or backward the lever 22', in maintaining a fixed perpendicular position, establishes relative longitudinal motion in one direction or the other whereby 20 the control lever 22 is operated automatically to adjust the elevator or horizontal rudder 11 to bring the machine back to a normally balanced position. The aviator may also, through the medium of the lever 25 25, operate the elevator or horizontal rudder to manually control the machine for an up-and-down steering action and for maintaining longitudinal stability.

Suitably arranged at the ends of the supporting surface are ailerons or balancing planes 24 which are mounted to swing vertically on horizontal transverse axes extending perpendicular to the line of flight, and these ailerons or balancing planes are connected by means of pitman rods 25 with cranks 26 upon rock shafts 27 which are provided with other crank arms 28 pivotally coupled to the opposite ends of a sliding rod or shaft 29. This rod or shaft 29 is disposed 40 at the rear of the main frame and is slidably mounted for movement in a direction transverse to the line of flight in anti-friction guides or bearings 30, the intermediate portion of said rod being slidably and pivotally connected to the upper end of a 45 weighted pendulum lever 31, which is mounted to swing in a fore-and-aft direction. The connections between the sliding rod and respective ailerons are such that when the 50 ailerons are disposed in a normal or neutral position the weighted lever 31 will be disposed and maintained by gravity in a perpendicular position, which position it will always assume, but when the machine tilts laterally in one direction or the other a relative motion between the lever and shaft and rod or shaft will be established, whereby the rod or shaft will be moved in one direction or the other, thus depressing the ailerons at 55 the lower side of the machine and raising the aileron at the high side of the machine, so as to respectively obtain lifting and depressing actions at the opposite sides of the machine to return the same to a normally balanced position. This operation will be

obtained in the tilting of the machine in either direction, so that when the machine tilts laterally in either direction beyond a determined angle the automatic controlling means will be set into action to easily and quickly right the machine. A locking device 32, having a pair of divergent extensions, movable toward and from the lever, is provided for locking or releasing said lever, and this device is movable through the medium of a controlling lever 33 provided with a locking dog or pawl 34 to engage a fixed rack 35, whereby the locking device may be projected or retracted and locked in either position. When projected the locking device will engage the lever 31 and hold the same from swinging movements, so that said lever may be maintained in a neutral position in which the ailerons lie at a neutral angle, allowing the aviator to fix the ailerons against automatic movement when the motor accidentally stops and it is necessary to 70 plane to earth or to perform other evolutions in which it is necessary or desired to temporarily dispense with the lateral controlling devices. In cases of emergency the lever may be operated by hand to adjust the ailerons for a manual controlling action.

It will be seen that by moving the lever 32 into a partial engaged position of the divergent extensions, the controlling connection of the lever 31 may be restricted to any desired degree, the lever 31 being locked in the particular position when desired by engaging the dog 34 with the rack 35.

From the foregoing description, taken in connection with the drawings, the construction and mode of operation of my improved aeroplane will be readily understood, and it will be seen that the invention provides an aeroplane which embodies simple and effective means for automatically maintaining both longitudinal and lateral stability thereof, so that when desired the aviator may allow the machine to run free from manual control without material danger of accident, and so as to permit him to have free use of his hands in making observations, collecting and inscribing data, firing a gun or performing other services requiring the use of both hands at a time. Also it will be seen that as the weights are also located and proportioned as to perfectly balance the machine, a useful load weight of quite a considerable amount may be carried at a low 115 resistance and high speed, thus adapting the machine for military, postal and express service where both speed and load carrying capacity are desired factors. For the purpose of controlling the machine in launching and landing, brake devices 38 may be provided to act upon the wheels 6, and these brake devices may be controlled by suitable connections from a foot lever 39 arranged so as to be conveniently operated by the avia- 120 125 130

tor, whereby the brakes may be set and released in a ready and convenient manner.

I claim:—

1. The combination with the controlling surfaces of an aeroplane, of a weighted lever, means whereby said lever is adapted for controlling said surfaces, and manually operable means adapted for movement to a plurality of operative positions to restrict said lever to a desired range of action, said manually operable means adapted to permit free controlling action of the lever within the particular range of action.

2. The combination with the controlling surfaces of an aeroplane, of a weighted lever, means whereby said lever is adapted for controlling said surfaces, manually operable means adapted for movement to a plurality of operative positions to restrict said lever to a desired range of action, said manually operable means adapted to permit free controlling action of the lever within the particular range of action, and means for locking said lever in any one of said positions.

3. The combination with the controlling surfaces of an aeroplane, of a pendulum, means whereby said pendulums are adapted for governing said controlling surfaces, a manually actuated lever disposed in proximity to said pendulum, divergent extensions on said lever adapted to be projected into the path of said pendulum to limit the movements of the pendulum, and means for locking said lever in any one of a plurality of positions whereby such limitation will be effective to a desired degree.

4. The combination with the controlling surfaces of an aeroplane, of a pendulum, means whereby said pendulum is adapted for controlling said surfaces, and a manually operable lever having divergent extensions adapted to be projected into the path of movement of the pendulum to limit the controlling action of the pendulum to a desired degree.

In testimony whereof I affix my signature.

JOHN F. KINNEY.
